UNITED STATES PATENT OFFICE.

WILLIAM S. MCLEWEE, OF NEW YORK N. Y.

FORCED-DRAFT LAMP.

SPECIFICATION forming part of Letters Patent No. 320,030, dated June 16, 1885.

Application filed April 4, 1884. (No model.)

To all whom it may concern:

Be it known that I, WILLIAM S. MCLEWEE, of New York, in the county and State of New York, have invented a certain new and useful Improvement in Lamps, of which the following is a specification.

I will describe a lamp embodying my improvement in detail, and then point out its various features in claim.

10 In the accompanying drawings, Figure 1 is a vertical section of a lamp embodying my improvement, and Fig. 2 is a horizontal section of the same.

Similar letters of reference designate corresponding parts in both figures.

15 A designates a base-piece of any suitable material—as, for instance, sheet metal. It is provided with suitable apertures or openings, *a*, for the entrance of air.

20 In the base-piece is a chamber, A', containing a train of wheel-work, B, and actuated by a spring or its equivalent. This chamber is provided with perforations *b*, through which air may pass.

25 Above the base-piece A is a shell, C, of sheet metal, shown as cylindrical at the lower portion and flaring at the upper portion.

D designates a reservoir for containing oil or other burning-fluid. It is arranged within 30 the shell C, and conforms to that part of the shell wherein it is located. It is provided with lugs *c*, which rest upon lugs *d*, extending from the shell. In this way the reservoir is supported in the shell. A space is left for 35 the circulation of air between the reservoir and the shell.

Below the reservoir and within the lower part of the shell are fans E F. The fan E is of large diameter, extending nearly across the 40 shell; but the fan F is of much smaller diameter. These fans are mounted on a shaft, G, which is rotated by the train of wheel-work B.

The reservoir is furnished with a burner, 45 H, which is here shown as having two wick-tubes, although it may have but one. This burner may be removably secured to the reservoir by screw-threads or other suitable means, and the opening wherein it fits may serve as 50 the filling-mouth for the reservoir.

The wick tube or tubes of the burner may

be provided with any suitable means for adjusting the wicks. As here shown, ratchet or star-toothed wheels arranged on shafts *e* are employed for this purpose.

55

The shell C is provided with a removable cover, C'. This cover is shown as secured in place by screw-threads *f*; but it may be secured in place by other means, or it may be merely slipped on. It extends over the top 60 of the reservoir at a suitable distance therefrom to allow of the circulation of air between it and the reservoir.

The cover C' has at the apex or center an air-chamber, I, extending to about a level with 65 the tip of the wick-tubes, and surmounted by a deflector, J, whereby air is caused to impinge upon the flames which emanate from the wick-tubes.

The air-chamber I is preferably formed in 70 two sections, the upper of which is connected to the lower by a hinge, *g*, and is capable of being secured to the other when closed by a spring-catch.

The upper section of the air-chamber may 75 be swung back to afford access to the tips of the wick-tubes.

In the upper section of the air-chamber is a 80 perforated diaphragm, K.

The deflector J has two slots, one over the 85 tip of each wick-tube.

The air set in motion by the fans E F rises through the shell to the burner and supports combustion.

No chimney or other draft-inducing device 85 is required.

A globe or shade may be used in conjunction with the burner, if desired.

By using two fans arranged one above the other upon the same shaft, one of which is of 90 smaller diameter than the other, I provide for subjecting all of the ascending column of air to the direct action of the fans.

I am aware that lamps have been constructed 95 provided with a train of wheel-work operating a single fan to set in motion a current of air for supporting combustion at the burner. I use two fans arranged one above the other, one of said fans being of smaller diameter than the other. When but one fan is used, much of 100 the ascending column of air is not brought within its influence as it passes upward near

the shaft upon which the fan is arranged, and so comes but slightly in contact with the blades of the fan which are narrowest at that point, and are there subjected to but slight motion as compared with the extremities of the blades. The smaller fan placed above the larger overcomes this difficulty, because thereby the entire area of the ascending air is energetically acted upon and a uniform upward impetus is imparted to the entire column of air.

What I claim as my invention, and desire to secure by Letters Patent, is—

In a lamp, the combination of a base pro-

vided with air-inlets, a train of wheel-work, two fans arranged one above the other upon the same shaft, one of said fans being of less diameter than the other, a reservoir, a burner on the reservoir, an air-chamber arranged about the burner, a perforated diaphragm within the air-chamber, and a deflector surmounting the air-chamber, substantially as specified.

W. S. McLEWEE.
